UNITED STATES PATENT OFFICE.

ADELBERT CHANDLER, OF AVONDALE, MISSOURI.

GRAIN-DOOR PULLER.

Application filed November 18, 1925. Serial No. 69,778.

This invention relates to grain door pullers of the general character disclosed in my United States Letters Patent issued to me on May 19th, 1925 and which has been given Number 1,538,024.

As is well known to the users of devices of this character, it is most necessary to provide a grain door puller which will effectively and positively engage and grip the grain door which is to be removed without breaking or otherwise mutilating the same.

It is the primary object of this invention to provide a grain door puller which has a portion adapted to engage the grain door at the inwardly facing side and adjacent the lowermost edge thereof, as well as to provide another engaging member which engages the grain door at the outwardly facing side and near the top edge of the door.

An even further object of this invention is the provision of a grain door puller which may be adjusted to engage either a single or a double thickness grain door.

A still further object of the instant invention is the contemplation of a grain door puller as above set forth which has an adjustable engaging bar provided with a pivotally mounted foot adjacent the pointed end thereof which may act as a safeguard against the possible splitting of the grain door when force is exerted and the pointed end of the bar is being driven into the door by this force.

Many minor objects will appear during the course of the detailed specification which refers to the accompanying drawing illustrating the preferred form of the invention and which is shown constructed to present a strong structure, one easy to make, effective in its operation and not likely to get out of order.

In the accompanying drawing:

Figure 1 is a vertical section through a grain door showing the grain door puller in side elevation and in position for receiving a lifting force.

Fig. 2 is a plan view of the grain door puller.

Fig. 3 is a vertical section of the grain door puller taken on line III—III of Fig. 1, looking in the direction of the arrow and with a portion of the grain door broken out to show the engaging bar which grips the door adjacent the lower edge, and,

Fig. 4 is an enlarged detailed, perspective view of the pivotally mounted foot car-

ried by the door-engaging end of the adjustable engaging bar.

With particular reference at this time to the drawings in detail wherein similar reference characters refer to like parts throughout the several views, the numeral 5 designates one of the two door posts of a box car against which the well known grain door 6 is nailed to preclude the grain which is loaded into the car from falling against the ordinary car door, not here shown.

It is well known that the grain door 6 must be forced inwardly and lifted before it can be removed from the position shown in Fig. 1. The weight of the grain bearing against door 6 requires the use of a strong and effective device of the character shown which is adapted to grip the door and receive the lifting power. In its preferred form the grain door puller should be constructed of metal and have a body member 7 which comprises a pair of spaced apart members angled slightly from the straight line as shown in Fig. 1. Connecting bolts 8 may be used to maintain the members of body 7 in the proper relative position as well as to afford an attaching means for a chain or similar member 9 which is engaged by hook 10 actuated to lift the entire device and grain door through any suitable connection to a source of power.

Engaging bar 12 is rigidly attached, and extends downwardly from one end of body member 7, by a bolt 13. Bar 12 may be rigidly held in position and strengthened by link 14 which is bifurcated at its lower end to pass on either side of bar 12 to be attached thereto by rivet or analogous means 15. The upper end thereof passes between the sides of body member 7 and is rigidly connected thereto by a bolt or rivet 16.

Another door engaging bar 17 is carried by body member 7 which passes between the members thereof near the end opposite from the attaching point of engaging bar 12. This adjustable bar 17 is provided with a plurality of holes 18 which pass therethrough to register with a hole of a similar size formed through the side members of body 7. In this instance but two holes 18 are shown, and the rear one is being used to hold bar 17 in a condition to effectively grip a single thickness grain door. When either of the holes in bar 17 registers with the hole in body member 7, a pin 19 may be passed there-

through to maintain the same in rigid assembled relation. This pin 19 may be hung to body member 7 by a flexible chain or the like 20. The forward or door engaging end of bar 17 is supported by a link 21 which pivotally inter-connects the same to body member 7 as shown in Figs. 1 and 3. This link keeps the door engaging end from dropping down around a center formed by 10 pin 19. Both engaging bars 12 and 17 are formed to present spurs 22 and 23 respectively, which embed themselves in the sides of the grain door when it is being pulled from its position. The engaging bar 12 is 15 provided with a shoulder 24 which precludes spur 22 from digging too deep into the door 6.

Obviously the greatest force is exerted against grain door 6 where engaging bar 20 17 engages the outer side thereof. To keep spur 23 from splitting or otherwise mutilating the door, a pressure equalizing foot 25 is pivotally mounted intermediate its upper and lower sides to bar 17 immediately before 25 spur 23. This foot 25 may be constructed in any suitable manner such as shown in Fig. 4, and the door engaging face thereof may be serrated as at 26 if desired.

30 Operation.

When it is desired to remove a grain door from a car of loaded grain it is but necessary to adjust engaging bar 17 to the proper thickness, force engaging bar 12 into the 35 grain immediately behind the door to a point where its spur 22 engages door 6 adjacent the bottom edge thereof. Spur 23 of engaging bar 17 is now in contact with the outer face of the door adjacent the upper edge thereof. That portion of the connecting chain 9 extending from hook 10 to near the upper end of engaging bar 12 is slack, and that portion extending from hook 10 to the outer end of body member 7 is tight. 40 It is plain to see that an upward pull on hook 10 will force both spurs 22 and 23 into the grain door 6, and an inward thrust against the upper edge thereof will be imparted through engaging bar 17. As power 45 is applied, the upper edge of door 6 will be forced through the arc of a circle having its center at the bottom edge of the door. The device of course should be affixed near one end of the door to force it inwardly and 50 upwardly before removing the opposite end.

What I claim and desire to secure by Letters Patent is:

1. A grain door puller having a body member adapted to pass over the top of the grain door, a pair of depending door engaging bars carried by said body member, said bars each having spurs at the end thereof to engage said grain door in the same vertical plane, one of said door engaging bars being 55 adjustable along a line substantially

parallel to the body member and engaging the grain door at the opposite side and above the other of said engaging bars.

2. A grain door puller comprising, in combination, a body member, means for connecting said body member to a source of power and means carried by said body member for engaging the grain door, said means including a pair of spurred bars one of said bars engaging said door at its one side adjacent the top thereof, the other of said bars engaging the door at its other side and adjacent the bottom thereof. 75

3. A grain door puller comprising, in combination, a body member, means for connecting said member to a source of power and means carried by said body member for engaging the grain door, said means including a bar rigidly carried by one end of said body member and adapted to engage the grain door at one side adjacent the bottom edge thereof and a bar adjustably supported at the other end of said body member and disposed to engage the grain door at its other side adjacent the top edge thereof. 80

4. A grain door puller comprising, in combination, a body member, means for connecting said member to a source of power, and means carried by said body for engaging the grain door, said means including a bar rigidly carried by one end of said body member and adapted to engage the grain door at one side and adjacent the bottom edge thereof and a bar adjustably supported at the other end of said body member and disposed to engage the grain door at its other side adjacent the top edge thereof, said adjustable bar having a support and guide link connecting its door engaging end to the body member. 90

5. A grain door puller comprising, in combination, means for connecting said member to a source of power and means carried by said body for engaging the grain door, said means including a bar rigidly carried by one end of said body member and adapted to engage the grain door at one side and adjacent the bottom edge thereof, and a bar adjustably supported at the other end of said body member and disposed to engage the grain door at its other side adjacent the top edge thereof, said adjustable bar having a series of holes therethrough adapted to register with an opening through the body member and a locking pin insertable through one of said holes and said opening. 105

6. A grain door puller comprising in combination, a body member, means for connecting said member to a source of power and means carried by said body for engaging the grain door, said means including a bar rigidly carried by one end of said body member and adapted to engage the grain door at one side and adjacent the bottom edge thereof. 110

edge thereof and a bar adjustably supported at the other end of said body member and disposed to engage the grain door at its other side adjacent the top edge thereof, said 5 adjustable bar having a support and guide link connecting its door engaging end to the body member, said link being pivotally attached to said body member and said adjustable bar whereby the engaging end of 10 said adjustable door engaging bar is mounted and maintained in the operative position.

7. A grain door puller comprising, in combination, a body member, means for connecting said member to a source of power, and means carried by said body for engaging the grain door, said means including a bar rigidly carried by one end of said body member and adapted to engage the 15 grain door at one side and adjacent the bottom edge thereof and a bar adjustably supported at the other end of said body member and disposed to engage the grain door at its other side adjacent the top edge 20 of said body member and adapted to engage the grain door at one side and adjacent the bottom edge thereof and a bar adjustably supported at the other end of said body member and disposed to engage the grain door at its other side adjacent the top edge 25 thereof, said adjustable bar having a support and guide link connecting its door engaging end to the body member and a serrated foot pivotally mounted intermediate

its ends to said adjustable bar, said bar having its door engaging end projecting beyond the face of said foot whereby the pointed end thereof is embedded in said grain door before the serrations of said foot engage the side thereof.

8. A grain door puller comprising, in combination, a body member, means for connecting said member to a source of power, and means carried by said body for engaging the grain door, said means including a bar rigidly carried by one end of said body member and adapted to engage the grain door at one side and adjacent the bottom edge thereof and a bar adjustably supported at the other end of said body member and disposed to engage the grain door at its other side adjacent the top edge thereof, said adjustable bar having a support and guide link connecting its door engaging end to the body member, said body member being formed of a pair of spaced apart parallel 45 members between which said adjustable bar is adapted to slide when being adjusted.

In testimony whereof I hereunto affix my signature.

ADELBERT CHANDLER.
